Patented Sept. 7, 1920.

UNITED STATES PATENT OFFICE.

ARTHUR T. CROCKER, OF SCHENECTADY, NEW YORK, ASSIGNOR TO GENERAL ELECTRIC COMPANY, A CORPORATION OF NEW YORK.

CONTROLLER FOR ELECTRIC MOTORS.

1,352,249.

Specification of Letters Patent.

Patented Sept. 7, 1920.

Application filed October 28, 1918. Serial No. 259,902.

To all whom it may concern:

Be it known that I, ARTHUR T. CROCKER, a citizen of the United States, residing at Schenectady, in the county of Schenectady,

5 State of New York, have invented certain new and useful Improvements in Controllers for Electric Motors, of which the following is a specification.

My invention relates to the control of electric motors and has for its object the provision of improved means whereby the motor may be started, stopped and generally controlled in a reliable, simple and efficient manner.

10 My invention relates more specifically to pneumatically operated controllers of the type in which a step-by-step movement is desired. In the pneumatically operated controllers, difficulty has been encountered 15 in securing a positive and definite stop, there being a tendency to over-travel, which results in trouble at the controller contacts. In the usual type of pneumatic engine, for instance, a piston is moved forward an increment 20 in a cylinder for each step of the controller, and it is difficult to insure that the piston shall move only the predetermined distance, since owing to the inertia of the parts, there is a decided tendency to over-travel.

25 In order to overcome this difficulty and at the same time provide a pneumatic engine which is very easily controlled, I employ a multiple cylinder engine which I have shown 30 as having three cylinders, 120 degrees apart, provided with a driving member which is acted upon successively by the pistons and so arranged that as each piston reaches the end of its stroke in driving the member forward, the member reacts equally on opposite 35 sides of the line of thrust of the piston, so as to positively stop the movement of the member without overtravel.

40 In one embodiment of my invention the driving member is in the form of a crank provided with two crank pins adapted to be engaged by a flat driving surface on each piston. When the driving surface of a piston in its forward thrust engages only 45 one of the pins it will rotate the crank until the other pin engages the surface, whereupon a balanced condition, in which there is no turning moment on the crank, will exist. This is the end of the stroke and 50 no amount of pressure against the piston or inertia of the parts will give the crank any 55 tendency whatever to overtravel. Furthermore, in this final position of the piston the two pins, although immovable by the piston which has just operated, are nevertheless in 60 operative relation to the two other pistons, one pin being engaged by each piston so that a forward movement of either piston will drive the crank. Not only will either 65 of the pistons now drive the crank, but 70 either a forward or reverse movement of the driving crank may be obtained depending upon which of the two remaining pistons is operated. At the end of any stroke, therefore, the engine may be reversed by 75 applying air pressure to the piston which operated the previous stroke instead of applying pressure to the next succeeding piston to give a forward movement. In addition to positively stopping the controller 80 at the end of each step, therefore, my invention constitutes a very convenient arrangement for reversing the movement of the controller. Other objects and purposes of my invention will appear in the course of the 85 following specification in which I have shown my invention embodied in concrete form for purposes of illustration.

In the accompanying drawings, Figure 1 is a sectional view of a pneumatic engine 85 through the cylinders embodying my invention, and Fig. 2 is a diagrammatic view illustrating the operation of the engine.

Referring to the drawings, 1 is a controller shaft driven by my pneumatic engine 90 through crank shaft 2 and gearing. This pneumatic engine comprises three cylinders 3, 4 and 5, mounted around the crank shaft, the center lines of the cylinders being radial to the center line of the shaft, at equal distance from each other, that is, 120 degrees apart. Pistons 6, 7 and 8 fit into the cylinders 3, 4 and 5 respectively, and are arranged to drive the crank shaft with a step-by-step movement, a complete stroke of each 95 piston corresponding to an angular movement of 120 degrees of the crank shaft. Each piston is single acting, that is, it drives in one direction only and is returned freely by the operation of the succeeding piston. 100 Instead of connecting the crank shaft with the pistons in the usual manner by a connecting rod journaled on the crank shaft, the crank is free with respect to the connecting rod, that is, the connecting rod pushes 105 the crank shaft forward but is not attached to it. The arrangement is such that when 110

the piston makes its complete stroke it is positively and accurately stopped. In this position the movement of one of the other pistons will turn the crank shaft in one direction, while the movement of the other piston will turn the crank shaft in the opposite direction. The particular connection between the pistons and the crank shaft which I have illustrated comprises a triangular shaped member 9 provided with rollers 10 and 11 at two of the corners, while the third corner is secured to the crank shaft 2. The pistons are provided with driving heads 12, 13 and 14, each having an elongated shank 15 pivoted to its piston at 16. These driving heads slide in guides 17 and have flat driving surfaces which engage the rollers 10 and 11.

The operation of my improved positive stop arrangement will be clearly understood from a consideration of Fig. 1. In this figure, piston 6 has completed a stroke and the two rollers 10 and 11 both engage the flat surface of the driving head 12 at equal distances on opposite sides of the center line of the piston. The piston, therefore, has no turning moment whatever upon the crank shaft, but on the contrary if air pressure is maintained on the piston it has a positive stopping effect depending upon the distance apart of the rollers 10 and 11 and to a certain extent upon the pressure applied to the piston. It will be further noted from Fig. 1 that while the crank shaft member 9 is in a position of equilibrium with reference to the driving heads 12, this is not true with reference to the driving heads 13 and 14. The roller 10 on the crank member engages the driving head 13 to the left of the center line of thrust, so that any forward movement of this head will drive the crank member, and hence the crank shaft, in a clockwise direction, whereas the roller 11 occupies an opposite position with reference to driving head 14, and hence a forward movement will drive the crank member in the opposite direction, providing pressure is not maintained against piston 6. This same relative position of the parts is assumed at the end of each stroke, so that by supplying pressure to one of the two pistons which are in retracted or operative position, the crank will be turned in one direction, while by supplying pressure to the other it will be turned in the opposite direction.

In Fig. 2 I have illustrated diagrammatically a valve arrangement whereby the admission of the air to an exhaust from the cylinders is controlled. Referring to this drawing it will be seen that I have provided two electromagnetic valves, which I shall designate as a whole as A and B respectively. These valves are normally held in an open position by springs *a* and *b* respectively. I have shown these valves only diagrammati-

cally in order to illustrate their function and have not attempted to show their structural arrangement. Each of these valves has two positions, one of which it assumes when its winding is energized and the other when it is deenergized. Valve B is shown for purposes of illustration and to facilitate an understanding of the arrangement as a triple valve, that is, there are three movable members 20, 21 and 22, one for each cylinder, whereas the valve A is shown as having only a single valve member. If the two valves A and B are both in the same position, air is admitted to a cylinder and the crank shaft will be rotated, the direction depending upon the position of the valves. If they are both in the energized position, the movement will be forward, whereas if they are both in deenergized position the movement will be reversed. As shown in Fig. 2, for instance, the valves are both in energized position and air is admitted to cylinder 3 so as to give a forward or clockwise rotation, but if the valves were both in deenergized position, the cylinder 4 would receive air and the direction of rotation would be reversed. If, therefore, the two valves were left in either the energized or deenergized position, the shaft would continue to rotate in either a forward or reverse direction until it reached a positive stop, whereas if the valve B alone be moved to the opposite position without changing valve A, or if the two valves occupy opposite positions, the operation of the engine will be stopped. The arrangement which I employ, however, is such that while valve A is left in one position, when a movement of the controller through more than one step is desired, the valve B is moved to deenergized position automatically at each step and is restored by the operator, thereby giving a step-by-step movement to the crank shaft under the control of the operator.

The arrangement whereby the magnet winding of valve B is controlled at each step is illustrated in Fig. 2, from which it will be seen that the circuit of the winding is controlled by switch arm 23, pivoted at 24. The switch arm is normally held in closed position by spring 25, and is opened by the rotation of a star wheel 26, having teeth corresponding with the steps of the controller and rotating therewith. As shown, a projection 27 (a roller in Fig. 1) engages the teeth of the star wheel and lifts the switch arm to open the circuit of the magnet B at contacts 28. When it is lifted, however, it is held in raised position by a magnet 29 which is energized from the master controller C direct to ground. In order to take another step, therefore, the magnet 29 must be deenergized by the operator so as to permit the spring 25 to force the switch member to closed position. As

each step is made, therefore, the master controller being in position 2, the circuit of the winding of valve B is automatically opened by the star wheel and is closed by 5 the operator moving the master controller back to position 1, thereby deenergizing magnet 29, and then back to position 2 which reenergized winding B. The result is that the controller takes a step at a time 10 in accordance with the movements of the master controller by the operator from position 2 to position 1 and back.

I shall now describe in detail the arrangement of the valves and air passages whereby 15 the result above described is accomplished. For purposes of illustration I have shown the rotating valve as being composed of an outer ring or passage 30 connected with a segmental passage 31. These 20 two passages are shown shaded and receive air from the reservoir through valve A and conduit 32. There is also an inner ring 33 and an outer segmental ring 34 connected to it, which I have shown stippled, this being 25 connected with the valve A by conduit 35. Valve A being in its energized position, therefore, as shown in the drawing, the shaded passages will receive air under pressure from the reservoir, whereas if the valve 30 A is in its upper or deenergized position, the stippled passages will receive air under pressure from the reservoir. When one passage is connected with the reservoir the other is connected with the exhaust. There 35 is also a segmental passage 36 which I have shown dotted, and which is connected to the exhaust, for purposes which will hereinafter appear. It will be understood, of course, that these circular passages form part of a 40 sliding valve which revolves 120 degrees at a step, that is, 120 degrees upon each complete stroke of a piston, and that the conduits connected with these passages are stationary.

45 Assume now the parts in the position shown in the drawing, the winding of the valves A and B being energized, air under pressure will enter the conduit 32 through the valve A, thence through the outer passage 30 to the inner passage 31, conduit 37, to the valve member 21, through the conduit 38 to the cylinder 3. Since both of the other cylinders are now connected to exhaust (cylinder 4 through conduit 39, valve member 22, conduit 40, through the passage 36 to exhaust 36', and cylinder 5 through conduit 41, valve member 20, conduit 42, passages 34 and 33 and conduit 35), the piston 6 will be forced forward rotating the 50 crank shaft in a clockwise direction as shown in Fig. 2. The piston 8 of cylinder 5 which has just made a stroke is at the limit of its movement and is, therefore, forced backward and the piston 7 of cylinder 4 is near its inward limit and is forced

back slightly. As the piston 6 moves forward its full stroke, the shaft will be rotated in a manner heretofore described. As the shaft moves forward the magnet winding B is deenergized at the contacts 28 and 70 the valve B moves to its opposite direction, the result of which is to interrupt the passage from the conduit 37 to conduit 38, and open conduit 38' which is now in engagement with passage 31 to conduit 38, thus 75 maintaining air pressure in cylinder 3. The cylinder is not, however, exhausted, as air pressure remains in the cylinder. It will be understood, of course, that during this step the sliding valve will revolve 120 degrees so that the end of the passage 31 passes into coöperating engagement with the conduit 40 which, however, is now cut off from cylinder 4 by the valve member 22. If the operator desires to move another 80 step, he moves the master controller back to position 1 to deenergize the winding 29, and then back to position 2, so that the circuit of the winding of valve B will be again completed, thereby leaving the valves A and B 85 once more in energized position. The passage is now open from conduit 40 to cylinder 4 so that the piston 7 moves forward and at the same time cylinder 3 is exhausted through the conduit 37 which is now in 90 engagement with passage 34 so that the exhaust takes place through conduit 35. The result is that the controller moves forward another step. In the same way by moving the master controller to position 1 and back 95 to position 2, the air pressure will be admitted to cylinder 5 through conduit 42, which upon the second step will be in engagement with passage 31.

Suppose now that instead of going continuously forward the operator wishes to reverse. Assume that the parts are in the position shown in Fig. 2, that is, a stroke has just been completed by the piston 8, but the winding of the valve B has not yet 100 been energized by moving the master controller from position 1 to position 2, and hence the valve is in the upper position. In other words, the operator has not yet moved the master controller to energize the 105 valve B to move forward, but instead deenergizes the winding of valve A by master controller to off position to go backward. The valves A and B will now both be in the deenergized position which is the 110 opposite to that shown in the drawing, so that the air pressure instead of being admitted to cylinder 3 will be admitted to cylinder 4 through conduit 35, passage 33, passage 34, conduit 43, valve member 22 and 115 conduit 39. This will drive the shaft in a counter clockwise direction step-by-step, and will continue to operate automatically 120 in that way if the operator keeps the master controller in the off position. To stop, 125 130

the master controller is moved to position 1, and to restore the forward movement the master controller is moved to position 2. In this way the controller will be moved forward one step at a time in either direction at the will of the operator.

It will be seen that I have provided a pneumatically operated controller in which a positive step-by-step movement is brought about under the control of the operator, the arrangement being such that there is no possibility of over-travel, while at the same time being very effective and simple.

While I have described my invention as embodied in concrete form and as operating in a specific manner in accordance with the provisions of the patent statutes, it should be understood that I do not limit my invention thereto, since various modifications thereof will suggest themselves to those skilled in the art without departing from the spirit of my invention, the scope of which is set forth in the annexed claims.

What I claim as new and desire to secure by Letters Patent of the United States is:—

1. A circuit controller comprising a controlling member, a plurality of fluid actuated reciprocating pistons for successively rotating the member, and driving connections between the pistons and the controlling member whereby at the end of each piston stroke the controlling member reacts equally on opposite sides of the line of centers of the piston and controlling member to positively stop the controlling member without over-travel.

2. A circuit controller comprising a controlling member, a plurality of fluid actuated reciprocating pistons for successively rotating the member, and driving connections between the pistons and the controlling member whereby at the end of each piston stroke the controlling member reacts equally on opposite sides of the line of centers of said piston and controlling member and reacts against each of the other pistons on one side only of its line of centers.

3. A circuit controller comprising a controlling member, a crank shaft for driving the same, a plurality of fluid actuated pistons reciprocating radially of said shaft and driving connections between the piston and the crank shaft whereby at the end of each piston stroke the crank shaft reacts equally on opposite sides of the line of centers of the piston and crank shaft to positively stop said shaft without over-travel.

4. A circuit controller comprising a controlling member, a rotating crank for driving the same, a plurality of fluid actuated reciprocating pistons for successively rotating the crank, and driving connections between the pistons and the crank whereby at the end of each piston stroke the crank re-

acts equally on opposite sides of the line of centers of the piston and crank to positively stop the crank without over-travel.

5. A circuit controller comprising a controlling member, a rotating crank for driving the same having two driving pins one for each direction of rotation, a plurality of fluid actuated reciprocating pistons and connections whereby a stroke of each piston acting through one pin rotates the crank in one direction and a similar stroke through the other pin rotates it in the opposite direction.

6. A circuit controller comprising a controlling member, a crank shaft and a crank thereon for driving the same provided with two crank pins in triangular relation with the shaft, and a plurality of fluid actuated reciprocating pistons driving said crank by engaging one of said crank pins and rotating the crank until the other crank pin is similarly engaged.

7. A circuit controller comprising a controlling member, a rotating crank for driving the same having two driving pins one for each direction of rotation, a plurality of fluid actuated reciprocating pistons and connections whereby the piston under pressure will engage one of said driving pins and rotate the crank until the said piston engages the other driving pin.

8. A circuit controller comprising a controlling member, a plurality of fluid actuated reciprocating pistons, each having a flat driving surface associated therewith, and driving pins for the controlling member, one of which is engaged by each flat surface to rotate the member until another pin engages the surface and positively stops the member.

9. A circuit controller comprising a controlling member, a plurality of fluid actuated reciprocating pistons each having a flat driving surface associated therewith, a rotating crank provided with two pins in triangular relation with reference to the axis of the crank, one of which is engaged by each flat surface to rotate the crank until the other pin engages the surface and positively stops the crank.

10. A circuit controller comprising a controlling member, three fluid actuated radially reciprocating pistons each having a flat driving surface associated therewith, a rotating crank provided with pins in triangular relation with reference to the axis of the crank, each of which is engaged by the flat surface of a piston at the beginning of a stroke and both simultaneously engaged by the flat surface of the piston which is at the end of its stroke.

In witness whereof I have hereunto set my hand this 26th day of October, 1918.

ARTHUR T. CROCKER,
